CLAIM

The ornamental design for a rack for holding leftover food containers for refrigerated storage, as shown.

DESCRIPTION

FIG. 1 is a top, front and left side perspective view of a rack for holding leftover food containers for refrigerated storage showing my new design;

FIG. 2 is a front elevational view thereof;

FIG. 3 is a top plan view thereof;

FIG. 4 is a right side elevational view thereof, the opposite side being a mirror image;

FIG. 5 is a rear elevational view thereof; and

FIG. 6 is a bottom plan view thereof, on a reduced scale.

FIGS. 2, 3 and 5 are shown broken away for ease of illustration only.
